EV RAND H. KERNS, OF WEEDSPORT, NEW YORK.

BARREL-HOOP FASTENER.

1,160,904.

Specification of Letters Patent.

Patented Nov. 16, 1915.

Application filed October 17, 1913. Serial No. 795,669.

To all whom it may concern:

Be it known that I, EV RAND H. KERNS, of Weedsport, in the county of Cayuga, in the State of New York, have invented new and 5 useful Improvements in Barrel-Hoop Fasteners, of which the following, taken in connection with the accompanying drawings, is a full, clear, and exact description.

This invention relates to certain improvements in fasteners for barrel hoops, in 10 which the fastening members are interlocked with the chime and extend downwardly a limited distance along the outer face of the staves to which their lower ends 15 are detachably secured by staples or equivalent fastening means, while the intermediate portions of the fastening members are provided with outwardly projecting spurs or serrations over which the hoops are adapted 20 to be driven and with which they frictionally engage to prevent accidental endwise displacement in the handling of the barrel.

The main object is to provide a simple 25 and comparatively inexpensive hoop fastener which may be quickly and economically applied to the staves of a barrel to receive and retain the hoops without nailing the latter to the staves.

Another object is to enable these hoops to 30 be easily and quickly removed with the fasteners by simply withdrawing the staples by which the lower ends of the fasteners are secured to the staves, thereby preserving the hoops, staves and head intact for re-use 35 in case it should be necessary to remove the hoops and head.

A further object is to utilize the overturned ends which interlock with the chime for retaining the head in operative position 40 against outward displacement.

Other objects and uses will be brought out in the following description.

In the drawings—Figure 1 is a side elevation of the upper portion of a barrel showing 45 a series of, in this instance three, hoops held in place by one form of my improved fastening means. Fig. 2 is an enlarged sectional view through the upper portion of the same barrel. Fig. 3 is a perspective view of 50 one of the detached hoop fasteners shown in Figs. 1 and 2, as made of sheet metal. Fig. 4 is a perspective view of a modified form of fastener made of wire, but performing the same functions as the device shown in 55 Fig. 3. Fig. 5 is a further modified form of fastener made of wire with a single spurred

shank. Fig. 6 is another modified form of fastener made of wire and having two spurred shanks terminating in head-retaining 60 ing arms.

The hoop fasteners shown in Figs. 1, 2 and 3 comprise a sheet metal plate —1—, of sufficient length to receive one or more hoops when arranged in proximity to each other and to the head of the barrel, these 65 plates being applied to the chime and stave of the barrel suitable distances apart as shown more clearly in Fig. 1 in which four of the fasteners are employed and spaced equal distances apart circumferentially of 70 the barrel.

The upper end of the plate —1— is provided with one or more, in this instance two, in-turned flanges or arms —2— for interlocking engagement with the chime as —a— 75 of a barrel —A— and is also provided with an out-turned bendable arm or tongue —3— adapted to be overturned against the outer edge and adjacent outer face of the end hoop after the latter has been placed in operative position by driving or otherwise 80 along and upon the outer surface of the plate —1—.

The main body of each plate lies along 85 and in close proximity to the outer faces of the adjacent staves and is provided with a series of outwardly and downwardly inclined spurs or teeth —4— over which the hoops as —b— are driven and by which said 90 hoops are retained and in place against endwise displacement, the lower or inner ends of the plates being fastened to the adjacent staves by removable fastening means as staples —5— which are driven through apertures —6— in the lower end of the plate 95 so that if it is desired to remove the hoops, it is simply necessary to withdraw the staples —5— whereupon the hoop-fastening plates —1— may be drawn upwardly with hoops 100 locked thereto until disengaged from the barrel.

The in-turned arms or flanges —2— are of sufficient length to engage a head-retaining segment —7— for holding the head in operative position against outward displacement, said segments being in this instance formed of wire and lie close against the outer edges of the head and adjacent portions of the chime and may enter the annular groove or crozing as —8— in the inner 110 faces of the staves in which the edge of the head is seated.

The hoop-retaining arm —3— of each plate is preferably left straight in alignment with the main body while all the hoops are being driven downwardly upon the outer faces of the plates and in contact with the spurs —4— but when the last hoop is driven in place with its outer edge substantially coincident with the corresponding edge of the chime, the arms —3— of each plate are bent over and downwardly against the upper edge and outer surfaces of the adjacent hoop to additionally lock the outer hoop, and thereby the remaining end hoops against endwise displacement.

The modified form of hoop fasteners shown in Fig. 4 is made of wire and comprises opposite lengthwise bars —9— spaced some distance apart, and a central lengthwise bar —10—, the lower ends of said bars being brought together by twisting at —11— so as to form a unitary fastener, said twisted portion terminating in an upturned shoulder —12— to form a limiting stop or abutment for the staple as —5— by which said lower end of the fastener is secured to the adjacent stave of the barrel. The upper ends of the bars —9— are over-turned inwardly and downwardly and united by a cross bar —13— adapted to engage the upper face of the segment —7— or head as —b'— of the barrel to hold the latter against outward displacement in the groove or crozing —8—. The outer surfaces of the bars —9— are also provided with outwardly and downwardly inclined spurs —4'— serving the same purposes as the spurs —4— for retaining the hoops in operative position on the barrel against endwise displacement. When the hoops are placed in operative position in the manner just described, the outer end of the bar —10— is overturned outwardly in a manner similar to that described for the tongue —3— to engage the adjacent outer edge and outer face of the end hoop —b— for additionally retaining the hoops against endwise displacement.

The modified form of fastener shown in Fig. 5 consists of a single wire rod —14— having its lower end provided with an eye —15— forming an abutting shoulder for the staple —5— which is adapted to be driven into the staves of a barrel, the upper end of the rod being deflected laterally and then returned inwardly and laterally to form a cross bar —13'— terminating in a loop —16— which returns against the adjacent side of the upper end of the bar or rod —14—, thereby producing with the opposite side a Y which together with the cross bar —13'— interlocks with the chime of the barrel with the cross bar —13— resting against the segment —7— or head of the barrel to retain the latter in operative position against endwise displacement, the outer face of the main body of the bar —14— being

provided with outwardly and downwardly projecting spurs —4'— similar to those shown in Fig. 4.

In the modification shown in Fig. 6, the fastener comprises a U-shaped wire rod having the cross bar at its base secured to the staves by a staple —5— and the upper ends of its arms returned inwardly and downwardly to form chime-engaging loops —18— terminating in laterally projecting arms —19— for engagement with the upper surface of the outer edge of the head of the barrel to hold said head in operative position against outward displacement, the arms being additionally secured in place to the staves or to the head by staples —5'—.

The outer surfaces of the opposite arms of the U-shaped rod —17— are also provided with outwardly and downwardly projecting spurs —4'— for the same purpose as the corresponding spurs shown in the modifications represented in Figs. 4 and 5.

It is now clear that in all of these several modifications, the hoops are held in place without nailing them to the staves and that the fasteners for the hoops serve the double purpose of retaining said hoops and also for holding the head against endwise movement. It is also clear that when it is desired to remove the hoops, it is simply necessary to withdraw the staples —5— whereupon the fasteners with the hoops attached thereto may be drawn upwardly until clear from the barrel, thus permitting the hoops to be removed without mutilating them or any other parts of said barrel.

What I claim is:

1. A fastening device for barrel hoops comprising a metal bar having one end over-turned for interlocking engagement with the chime of a barrel and its opposite end provided with means for attaching it to the staves of the barrel, the intermediate portion of said bar being provided with spurs protruding from its outer face for engagement with barrel hoops, said bar having its first-named end provided with a bendable tongue for engagement with the edge of the uppermost hoop.

2. In combination with a barrel having a head and staves, the latter being crozed to receive the head, a head-retainer running around the inside of the chime against the head, and a hoop fastener consisting of a bar having its upper end over-turned upon the chime and engaged with said retainer, and its lower end provided with means for attaching it to the staves, said bar having its intermediate portion provided with spurs protruding from its outer face for engagement with the hoops.

3. In combination with a barrel having a head and staves, the latter being crozed to receive the head, a head-retainer running around the inside of the chime against the

head, and a hoop fastener consisting of a bar having its upper end over-turned upon the chime and engaged with said retainer, and its lower end provided with means for attaching it to the staves, said bar having its intermediate portion provided with spurs protruding from its outer face for engagement with the hoops, the upper end of said bar being also provided with a bendable

tongue over-turned outwardly and engaged 10 with the upper edge of the uppermost hoop.

In witness whereof I have hereunto set my hand this 4th day of October, 1913.

EVRAND H. KERNS.
